UNITED STATES PATENT OFFICE

95,922

DESIGN FOR A CARD GAME SCORING BOARD

William Andrew O'Brien, San Pedro, Calif.

Application April 3, 1934, Serial No. 51,305

Term of patent 14 years

To all whom it may concern:

Be it known that I, William Andrew O'Brien, a citizen of the United States of America, residing at San Pedro, in the county of Los Angeles and State of California, have invented a new, original, and ornamental Design for Card Game Scoring Boards, of which the following is a specification, reference being had to the accompanying drawing, forming a part thereof.

Fig. 1 is a plan view of a card game scoring board, showing my new design,

Fig. 2 is a side elevation, and

Fig. 3 is a section through the board on the line 3—3 of Fig. 1.

I claim:

The ornamental design for a card game scoring board substantially as shown.

WILLIAM ANDREW O'BRIEN.
